UNITED STATES PATENT OFFICE.

EUGENE H. TAYLOR, OF BOSTON, MASSACHUSETTS.

PROCESS OF MAKING INSOLES.

1,145,094.

Specification of Letters Patent. Patented July 6, 1915.

Application filed August 10, 1914. Serial No. 856,134.

To all whom it may concern:

Be it known that I, EUGENE H. TAYLOR, a citizen of the United States, residing at Boston, county of Suffolk, State of Massachusetts, have invented a certain new and useful Improvement in Processes of Making Insoles, of which the following is a specification, reference being had therein to the accompanying drawings.

10 In United States Letters Patent to George Coleman No. 1,062,536, dated May 20, 1913, there is shown a composite insole composed of two layers of split or other thin leather. This insole is found to have many practical advantages and the material from which it is made is very cheap, but attempts which have been made to produce these insoles commercially by machine have failed. The machines for making these insoles have 15 formed the edges progressively beginning near the toe or heel and following around the edge. It has been found that satisfactory insoles cannot be produced by this method at a reasonable cost.

20 My invention, therefore, has for its object a new and improved method of making substantially the insole shown in said Coleman patent, which shall obviate the objections previously referred to. Accordingly, in 25 practising my invention I form at one time the entire folded edge of each of the members which together compose the insole, and then assemble and unite the two members.

30 My invention will be fully understood from the following description taken in connection with the accompanying drawings and the novel features thereof will be pointed out and clearly defined in the claims 40 at the close of the specification.

45 In the drawings,—Figure 1 shows the blank from which the inner member of the insole is produced. Fig. 2 is a view in perspective of said inner member in its finished form. Fig. 3 is a section on line 3—3 of Fig. 2. Fig. 4 is a plan view of a blank from which the outer member is formed. Fig. 5 is a view in perspective of the said outer blank. Fig. 6 is a section on line 50 6—6 of Fig. 5. Fig. 7 is a view in perspective of the completed insole composed by superposing the inner member shown in Fig. 2 on the outer member shown in Fig. 5, said two members being in proper rela-

tion one to the other. Fig. 8 is a section on line 8—8 of Fig. 7.

Referring now to the drawings,—in Fig. 1 there is shown a blank 11 for the formation of the inner member. This blank is slit at 12, 12 at about the line between the heel and the shank. The blank is properly tempered and while in this soft and pliable condition, is subjected to pressure and heat between suitable dies, one of which occupies the center 14 of the blank and the others of which turn up its margin to form a lip or feather 13. The blank is submitted to the pressure and heat between the dies for a length of time sufficient to give the parts a permanent set or shape. The inner member resulting from steps described so far is shown in Fig. 2.

In Fig. 4 there is shown a blank 15 from which the outer member of the insole is made. This blank is also properly tempered and is then subjected to pressure and heat between dies, one of which occupies the center 16 of the blank and is of a slightly smaller size than the area of the blank as determined by the outer periphery of the finished member. The other dies bend the margin of the blank over the edge of the inner die and turn it up to form a lip 17. The dies are then withdrawn leaving the blank in the shape shown in Figs. 5 and 6 with an edge portion 18 bent back upon itself from the edge of the insole and an upwardly projecting lip or feather 17.

The time, pressure, and heat to which the two blanks are subjected are all regulated as will be understood by those skilled in the art of handling leather, and the leather is given the desired permanent set and stiffness, its shape being determined by the shape of the dies. Thereafter, the inner member 90 95 11 is assembled within the edge of the outer member 15 and the two are preferably secured together by adhesive spread over their adjacent surfaces. The parts are again subjected to pressure and heat after being assembled so that they are then firmly united.

The herein described method may be best and most economically practised by having three machines all of the same general character one of which forms the inner, and another of which forms the outer member composing the finished insole and the third of which squeezes together the assembled parts.

I do not limit myself to the use of any particular machine for this purpose because the herein described novel process may be practised either by machine or by hand by the 5 use of suitable dies which are not incorporated in a machine.

I have found that the herein described method obviates the difficulties which have been found result from the former method 10 of forming progressively the edges of the two members composing the insole. By the employment of my method each member may be rapidly and almost instantly shaped and the members are always perfect 15 replicas of each other and do not vary in size or in any of their dimensions.

What I claim is:

1. The method of making a composite insole which comprises tempering a piece of 20 stock, forming an upwardly projecting rib about a portion of its periphery, the whole of said rib being formed at the same time by subjecting the blank to pressure and heat between dies, withdrawing the dies, insert-

ng within the shaped piece an inner piece 25 having an upwardly turned edge adapted to lie in contact with said rib, and subjecting both pieces to pressure to cause them to adhere.

2. The method of making a composite insole which comprises tempering a piece of stock, forming an upwardly projecting rib about a portion of its periphery, the whole of said rib being formed at the same time by subjecting the blank to pressure and heat 35 between dies, withdrawing the dies, inserting within the shaped piece an inner piece having an upwardly turned edge adapted to lie in contact with said rib, and subjecting both pieces to pressure and heat to cause 40 them to adhere.

In testimony whereof I affix my signature, in presence of two witnesses.

EUGENE H. TAYLOR.
